US0D1064819S

(12) **United States Design Patent** (10) **Patent No.:** **US D1,064,819 S**
(45) **Date of Patent:** **** Mar. 4, 2025**

(54) **CONTAINER LID**

(71) Applicant: **BWAY CORPORATION**, Atlanta, GA (US)

(72) Inventors: **Frano Luburic**, Costa Mesa, CA (US); **Forrest A. Burney**, LaGrange, GA (US)

(73) Assignee: **BWAY CORPORATION**, Atlanta, GA (US)

(**) Term: **15 Years**

(21) Appl. No.: **29/851,479**

(22) Filed: **Aug. 29, 2022**

(51) **LOC (15) Cl.** **07-05**

(52) **U.S. Cl.**

USPC **D32/54**

(58) **Field of Classification Search**

USPC ..... D9/434, 435, 436, 438, 439, 440, 446, D9/454; D7/387, 391, 392.1, 396.1, D7/396.2; D23/206, 209, 259, 260; D34/1, 6, 10, 29; D32/53, 54 CPC B65D 81/32; B65D 47/063; B65D 25/20; B65D 43/0218; B65D 43/32; B65D 17/08; B65D 17/4012; B44D 3/127; B44D 3/006; B65F 1/065; B65F 1/06

(57) **CLAIM**

The ornamental design for a container lid as shown and described.

DESCRIPTION

FIG. 1 is a top perspective view of a container ring showing our new design;

FIG. 2 is a bottom perspective view thereof;

FIG. 3 is a top view thereof;

FIG. 4 is a bottom view thereof;

FIG. 5 is a side view thereof; and,

FIG. 6 is a cross-sectional view thereof, taken along line 6-6 in FIG. 3.

The dot-dash broken lines represent the designation of an enlarged cross-sectional view and form no part of the claimed design.

1 Claim, 6 Drawing Sheets
